SHOE SOLE CONSTRUCTION

Meyer Margolin, Elgin, Ill.

Original application February 8, 1941, Serial No. 377,948. Divided and this application January 16, 1943, Serial No. 472,541

4 Claims. (Cl. 36—3)

1

My invention relates to a novel resilient shoe insole and more particularly my invention relates to a novel combination of insole, outsole and filler, which combination is adapted to provide increased foot comfort in that a softer and more resilient cushion is provided for the foot and increased breathing and ventilation effected.

One form of my invention which I shall describe more specifically hereinafter is adapted to be employed in that type of shoe in which the insole is formed by splitting off a layer of leather from the outsole. The insole may be split from the outsole to provide a thin insole and a relatively thicker outsole, or the cleavage may be so effected as to provide a raised portion or island on the top or upper side of the outsole with a corresponding dished out concavity on the lower side of the insole. This raised portion or island may be so cut that the dished out concavity in the insole extends through the thickness of the insole and forms an opening in the center forepart thereof.

Between this outsole and insole I position a filler comprising a resilient rubber-like material which may contain constructional features such as grooves and perforations adapted to increase the resilience of this filler and provide for ventilation and forced breathing.

This filler may be provided on the underside with a dished out concavity adapted to fit over the island portion of the outsole and to be engaged thereby or the filler may be without such dished out concavity in which case the island or raised portion of the outsole acts to press the filler into the dished out concavity of the insole corresponding to the island on the outsole and in fact may press the filler above the plane of the insole to provide a raised resilient ball cushion support for the center forepart of the insole.

When the cleavage of the insole from the outsole is effected so that there is no island or raised portion of the outsole or when an ordinary outsole is employed with an insole which is cut out at the centre portion of its forepart to provide a dished out concavity which may or may not penetrate through the thickness of the outsole to provide an opening therein, I may then employ a filler, the central portion of which is substantially thicker than the edge portion and tapers down from the center to such relatively thin edges.

It is also within the purview of my invention to provide a metatarsal support element which is formed integrally with the filler and disposed in the proper position thereon.

Although I have above discussed my invention with reference to the use of a filler, it is also to be understood that I may form an insert for an insole which has a dished out opening, in which case I employ the construction above set forth.

The advantages of the constructions as out-

2

lined above are manifold. First, I provide for a greatly increased flexibility in the outsole-insole combination and this flexibility is greatest in the center of the forepart of the insole where such flexibility is desired. Second by my construction I provide for greatly increased resilience and softness of step for the shoe employing this construction and this resilience and softness is greatest at the ball portion of the foot which is adapted to take the impact of the foot in walking. The resilience tapers down from this ball portion to the peripheral portion of the filler where the filler approaches a feather edge thinness. Third, my construction provides for increased ventilation and breathing in these shoes of the so-called one piece sole type.

The filler of my invention may be positioned not only under the forepart of the insole but it is also within the purview of my invention to employ this resilient member in the heel portion of the shoe or to provide a single unit extending from heel to toe between the outsole and the insole.

This application is a division of my co-pending application Serial No. 377,948, filed February 8, 1941, for Resilient insert-insole combination, which is now Patent No. 2,308,529, dated January 19, 1943, and which is a continuation in part of my copending application Serial No. 306,778, filed November 30, 1939, for Novel insole and outersole combination.

It is the object of my invention to provide a novel resilient combination of outsole, insole and filler.

It is a further object of my invention to provide a novel filler for a so-called one piece sole.

It is a further object of my invention to provide a filler adapted to be positioned in a dished out concavity in an insole, said filler having a recess or concavity adapted to fit over or be engaged by a corresponding raised portion or island on an outsole.

It is a further object of my invention to provide a novel combination of plane outsole and an insole having a dished out concavity, in which dished out concavity is positioned a resilient filler having grooves and perforations for increased breathing effects.

It is a further object of my invention to provide a filler for an insole in which insole is cut a concave tapering opening.

It is a further object of my invention to provide a novel filler adapted to be positioned between the insole and the outsole, said filler carrying an integral support for the metatarsal arch.

These and further objects of my invention will become apparent from a consideration of the drawing and the specific description thereof which here follows:

Figure 1 is a central longitudinal cross section

3

of the combination of insole, outsole and filler of my invention.

Figure 2 is a top plan view of the insole of my invention showing the filler extending into the opening therein.

Figure 3 is a transverse cross section taken along the line 3—3 of Figure 2.

Figure 4 is a central longitudinal cross section showing a modified form of the filler of my invention.

Figure 5 is a longitudinal cross section showing a still further modified form of the filler of my invention.

Referring now more specifically to the drawing, in Figure 1 I show an outsole 1 having a raised portion, or island 5, in the center of the forepart thereof. An insole 3 which has been split from the outsole 1 has an opening 4 which corresponds to the island 5, the opening 4 having tapering side walls and extending through the thickness of the insole 3. A filler 2 is positioned between the outsole 1 and the insole 3 and the filler 2 is of such thickness that its upper portion is at least level with the plane of the upper side of the insole 3 and may extend slightly beyond this plane being pressed upwardly by the island 5. On the lower side of the filler 2 is a concavity 9 which is adapted to fit over and engage the raised portion or island 5. In the filler 2 are perforations 6 and grooves 7. Perforations 10 may be provided in the grooves to cause flow of air from the grooves into the interior of the shoe. Where the perforations, such as 6, in the filler 2 lie beneath the insole 3, then corresponding perforations 8 may be provided in the insole 3.

In Figure 4 I show an outsole 11 having a raised portion 14 at the forepart thereof and an insole 13 having a dished out concavity 12 which corresponds to the raised portion 14. A filler 15 which, unlike the filler 2 shown in Figure 1, is of substantially uniform thickness in its central body portion and has no dished out concavity, is positioned between the insole 13 and outsole 11 and is pressed upwardly by the raised portion 14 into the cavity 12 of the insole 13 so that it is pressed to at least the plane of the upper surface of the insole 13 and ordinarily rises slightly higher than the upper surface of the insole 13. This filler 15 tapers down at its periphery to a feather edge and as shown is stitched to the insole 13 at these edges by the stitching 16. Suitable grooves 17 and perforations 18, and the combination of perforations and grooves 19, are provided for ventilation and forced breathing effects.

In Figure 5 I show an outsole 20 having a substantially plane upper surface combined with an insole 21 having a dished out concavity 23 which extends through the thickness of the insole 21 and forms an opening in the center of the forepart thereof. A rubber-like insert 22 having its greatest thickness in the center tapering down to thin peripheral edges is secured in this opening 23 by stitching 24.

Grooves 25, perforations 26 and combined perforations and grooves 27 are formed in the insert 22 so that air is freely transmitted and pumped therethrough during the flexing of the unit in the act of walking. It will be noted that this insert gradually diminishes in thickness so that the greatest resilience of the unit is in the center of the forepart of the insole and by reason of the tapering or skived edges of the opening 23 in the insole 21 a greater area of resilience is obtained than is defined by the opening through the insole 21. In other words, the resilient area

4

extends for the entire area of the insert 22 and is not defined simply by the opening in the upper side of the insole 21.

The construction above shown and described in connection with Figures 1 to 5 may be also employed between the insole and the heel portion of the outsole in the heel area to provide for increased resilience and breathing in the heel. Similarly the filler may extend between the outsole and insole for the full length of the shoe, whereby these effects may be obtained throughout the length of the shoe.

I may additionally employ over this construction a resilient pad either of a rubber-like or fibrous material. The pad should be relatively thick towards the central forepart section and diminish in thickness towards the edge, the edge being of feather edge thickness. This resilient pad which may be termed an overlay pad may have a cookie or additional arch support in the region of the large arch and this pad may extend either in the forepart alone or from toe to heel. By means of the greater thickness in the region of the forepart, the weight of the body is properly distributed on the ball of the foot and a ball cushion support is given to the bottom of the foot. This pad may be perforated by a series of perforations extending through it so that in the act of walking the flexing or compressing of the resilient overlay pad produces a circulation of air in the shoe.

Various other modifications of my invention will suggest themselves to those skilled in the art. I accordingly desire that in construing the breadth of the appended claims they shall not be limited to the specific details shown and described in connection with the above explanation.

I claim:

1. In combination an outsole, a hump integral with said outsole on the upper central portion thereof, an insole, an opening in said insole corresponding to said hump and a resilient member between said outsole and insole, and said resilient member having a dished out cavity on the undersurface thereof.

2. In combination an outsole, a hump integral with said outsole on the upper central portion thereof, an insole, an opening in said insole corresponding to said hump and a resilient member between said outsole and insole, and said resilient member having a dished out cavity on the undersurface thereof, said cavity engaging said hump, grooves on the undersurface of said resilient member.

3. In combination an outsole, a hump integral with said outsole on the upper central portion thereof, an insole, an opening in said insole corresponding to said hump and a resilient member between said outsole and insole, and said resilient member having a dished out cavity on the undersurface thereof, said cavity engaging said hump, grooves on the undersurface of said resilient member, and perforations and grooves on the undersurface of said resilient member.

4. In combination an outsole, a hump integral with said outsole on the upper central portion thereof, an insole, an opening in said insole corresponding to said hump and a resilient member between said outsole and insole, said resilient member having a dished out cavity on the undersurface thereof, said cavity engaging said hump, grooves and perforations on the undersurface of said resilient member, and stitching joining said resilient member to said insole.
